238,120

PROTECTIVE HELMET OR THE LIKE

Jhoon Goo Rhee, 2525 N. Ridgeview Road,
Arlington, Va. 22207

Filed Nov. 27, 1974, Ser. No. 527,902

Term of patent 14 years

Int. Cl. D2—03

U.S. Cl. D2—232

FIG. 1 is a front elevational view of a protective helmet showing my new design;

FIG. 2 is a side elevational view thereof; and

FIG. 3 is a rear elevational view.

I claim:

The ornamental design for a protective helmet or the like, as shown.
